J. F. ROBERTS.
ROUTER FOR TRACTOR WHEELS.
APPLICATION FILED AUG. 17, 1921.

1,427,418.

Patented Aug. 29, 1922.

UNITED STATES PATENT OFFICE.

JOHN F. ROBERTS, OF FRESNO, CALIFORNIA.

GROUTER FOR TRACTOR WHEELS.

1,427,418.

Specification of Letters Patent. Patented Aug. 29, 1922.

Application filed August 17, 1921. Serial No. 492,977.

To all whom it may concern:

Be it known that I, JOHN F. ROBERTS, a citizen of the United States, and resident of Fresno, in the county of Fresno and the State of California, have invented a new and useful Improvement in Grouters for Tractor Wheels, of which the following is a specification.

My invention relates to traction wheels, and more specifically to that form of grouter the subject of my application for United States Letters Patent filed October 23, 1920, tractor wheels, Serial Number 418976, and filed May 3, 1921, grouter for a wheel, Serial Number 466427. In the inventions described in the applications filed I have broadly claimed a form of grouter hinged to the rim of the wheel and adapted to push downward into the earth as the wheel rotates on the ground. The object accomplished in the present invention is the construction of a form of grouter following the broad principle of the grouter described in my prior applications, but which is more easily assembled with the wheel and more easily removed therefrom, has less wearing parts, and is more cheaply constructed. I accomplish these objects by means of the device hereinafter described, and illustrated on the accompanying drawing in which Figure 1 shows a side view of a wheel having my improved grouters attached thereto. Figure 2 is an enlarged view of one of the grouters. Figure 3 is a sectional view of the rim of the wheel along the line $x-x$ in Figure 1. Figure 4 is a fractional view of the inside of the rim showing the expansion spring located at a different place than shown in Figure 1. Figure 5 is a fractional view of the inside of the rim showing a modified form of spring which may be substituted for the expansion spring shown in Figure 1.

In said drawing B represents a wheel having a hub B^1 , a plurality of spokes B^2 , and a rim B^3 . The rim is constructed with inside flanges C and C^1 on opposite sides thereof. D is a complete grouter unit. It consists of two arms 2 and 2^a , each of which terminates in a hook 3 at one end. A baffle blade 4 is attached to the arms at the other end so that the arms 2 and 2^a are on parallel planes a spaced distance apart. This space is large enough so that the rim of the wheel can readily pass between them. The

plane of the baffle blade describes an obtuse angle to the arms. Tie 5 connects arms 2 and 2^a adjacent to hooks 3 . Upright supports 6 and 6^a are attached to arms 2 and 2^a near the baffle blade 4 . It is preferable that upright supports 6 and 6^a be parallel. Rod 7 , extending from upright support 6 to support 6^a is pivoted therein so that it can turn axially. One end of rod 7 terminates with hook 7^a . Opposite to hook 7^a is a wire key 7^b adapted to hold rod 7 within the holes 7^c and 7^{cc} in upright supports 6 and 6^a . On flanges C and C^1 I have attached a plurality of projections 8 and 8^a , in pairs, equidistant apart, around the flanges. In Figure 3 I have shown a sectional view of a pair of said projections constructed of a bolt 8^e which carries a bushing 8^b . This form of projection can be substituted by numerous equivalents as the sole object to be accomplished is to form a projection to function as a pivot on which hooks 3 can swing. The drawing shows two endless chains 9 and 9^a , and a plurality of expansion springs 10 and 10^a . In assembling the grouters on the wheel the hooks 3 engage the projections 8 and 8^a so the grouter can swing freely thereon beyond the periphery of rim B^3 . Grouter D is then moved to a position so the baffle blade 4 is adjacent to the periphery of the wheel, and the rod 7 is inserted through the holes 7^c and 7^{cc} , and keyed therein with key 7^b . It will be noted that when the grouter is thus assembled with the wheel the tie 5 will act as a stop for holding the hooks 3 engaged with the projections 8 and 8^a when the baffle plate is swung toward the periphery of the wheel, and rod 7 will act as a stop against the flanges C and C^1 when the baffle plate has swung a spaced distance from the said periphery. One grouter is necessary for each pair of projections. It should also be observed that while the grouters are uniformly constructed, the rod 7 can be inserted through the holes 7^c and 7^{cc} with the hook 7^a on either side of the wheel. In assembling the grouters with the wheel, the hooks are placed on different sides on the grouters, as shown in Figure 4, but as disclosed later the hooks can all be assembled on one side of the wheel. When the grouters are hooked on extensions 8 and 8^a as described, with the rod 7 inserted as described with the hooks 7^a

alternating on two sides of the wheel, the endless chains 9 and 9^a are attached to the hooks 7^a, the one chain on either side. If the hooks are all arranged on one side of the wheel, the chains 9 and 9^a should be attached to alternate hooks or grouters. These chains are of such length that all of the grouters attached thereto are drawn and held adjacent to the periphery of the wheel except one which can swing downward when it comes in contact with the ground. The expansion springs 10 and 10^a are shown attached at one end to the wheel and at the other end to the chain. The function of these springs is to yieldably pull the grouters adjacent to the rim of the wheel. In Figure 1 I have shown these springs attached at one end to the chain between the points where it is attached to the hooks 7^a. This form can be modified by attaching the one end of the chain to hooks 7^a as shown in Figure 4. Other forms of springs which will accomplish the purpose sought may be used as spring 10^c shown in Figure 5. The object of the endless chains is to positively hold all of the grouters attached to the chain, except the one functioning in the earth, adjacent to the rim of the wheel. There is a special advantage in having two chains as shown in the drawing, each chain being attached to alternating grouters, for by this means two grouters can function at one time. It is also noted that in certain kinds of work the chains can be dispensed with and the springs will normally hold the grouters adjacent to the rim of the wheel.

Having described my invention, I claim as new and ask for Letters Patent:

1. In combination with a traction wheel having a rim, a plurality of pairs of projections around said rim a spaced distance apart, the projections on each pair being on opposite sides of said rim, a grouter constructed of two arms having hooked members at one end adapted to pivotally engage said projections, and a baffle blade at the other end, said arms being tied together a spaced distance apart, which distance is not less than the width of the rim, means for limiting the movement of the grouter toward and from the rim of the wheel, and yielding means for normally holding the grouter adjacent to the rim of the wheel, substantially as described.
2. In combination with a traction wheel having a rim and a plurality of pairs of outwardly extending projections attached to said rim equidistant apart, one projection of each pair being on each side of the rim, a grouter for each pair of projections, each grouter being constructed of two arms having hooks at one end adapted to pivotally engage a pair of said projections, a tie connecting the arms adjacent to the hooks a spaced distance apart and parallel to each other, a baffle blade attached to the arms and connecting them at the end opposite to the hooks, upright projections adjacent to the baffle blade, a rod connecting said arms near the tops thereof and adapted to form a stop against the inside of the rim, and yielding means for normally holding the baffle blade against the periphery of the wheel substantially as described.
3. In combination with a traction wheel having a rim, a plurality of pairs of outward projections around said rim a spaced distance apart, one projection of each pair being on each side of the rim, a plurality of grouters, each grouter consisting of two arms tied a spaced distance apart parallel with each other, said arms having a baffle blade attached at one end and at the other end hooks adapted to pivotally engage a pair of said projections, an upright guide attached to each arm, one of which is adapted to be on each side of said rim when the grouter is assembled therewith, means for limiting the pivotal movements of the grouter, and yielding means for normally holding the baffle blade against the periphery of the wheel, substantially as described.
4. In combination with a traction wheel having a rim, a plurality of pairs of outward projections around said rim equidistant apart, one projection of each pair being on each side of the rim, a plurality of grouters, each grouter constructed with two arms, having hooks at one end and a baffle blade at the other end, said arms being tied together so that the hooks on the grouter arms can pivotally engage a pair of the projections said arms being rigidly tied together, upright guides attached to the arms adapted to pass on each side of the rim as the grouter swings on said pivotal projections, an endless chain arranged on each side of the wheel to which an upright guide of alternate grouters are attached, said chain being of such length that when all of the grouters are pulled by the chain against the periphery of the wheel one grouter attached to said chain can swing on its pivot a spaced distance, substantially as described.
5. In combination with a traction wheel having a rim, a plurality of pairs of projections extending outwardly from said rim and on opposite sides a spaced distance apart, a plurality of grouters constructed with two arms tied together a spaced distance apart parallel with each other, having hooks at one end adapted to pivotally engage a pair of said projections and having a baffle blade at the other end so that when the grouter is swung with the baffle blade adjacent to the periphery of the wheel the plane of the baffle blade will be approximately on line with a radius of the wheel, stop means for limiting the distance the baffle blade can be swung from the periphery of the wheel,

and means for holding a predetermined number of the grouters with the baffle blade against the periphery of the wheel while a predetermined number of said grouters are 5 adapted to be swung within said prescribed limits, substantially as described.

6. In combination with a traction wheel having a rim, a plurality of pairs of outward projections around said rim equidistant apart, one projection of each pair being 10 on each side of the rim, a plurality of grouters, each grouter constructed with two arms, having hooks at one end and a baffle blade at the other end, said arms being tied 15 together so that the hooks on the grouter

arms can pivotally engage a pair of the projections said arms being rigidly tied together, upright guides attached to the arms adapted to pass on each side of the rim as the grouter swings on said pivotal projections, two endless chains of uniform length attached to the grouters, the alternate grouters being attached to different chains, said chains being of such length that when one grouter is swung from the periphery of 20 the wheel within the fixed limitation, all the other grouters attached to the same chain will be drawn against the periphery of the wheel, substantially as described.

JOHN F. ROBERTS.
